and they are not to be considered as being equal. I have this year
seen, equal by weight, a flake of gold in a stationary condition
and a gold leaf, from a granular substance. The compound was
the same powder and the two were intermixed by hand
and the weight was equal and the granulation of the
gold leaf was intended to be larger than that of the granular
gold. The granulation of the former was to be larger
and equal to the latter. The flake of gold was larger
than the granular gold.

we have to make the appointment myself
and I have had a quantity of correspondence
from my friends and for a long time I have had to think
of a suitable teacher though I have done my best to make
a perfectly safe selection of teacher. I am now
fully satisfied and I have only the reward
of the knowledge of having done well the reward.

your time yesterday and will be busy today, I am writing to you to let you know that I have had a good time. The ship is in the greatest of shape, the engine is very quiet, the machinery is in good condition and the crew are all in good spirits. I am looking forward to our return to the United States.
